APPARATUS FOR COILING STRANDS

George E. Henning, Baltimore, Md., assignor to Western Electric Company, Incorporated, New York, N.Y., a corporation of New York

Application July 9, 1958, Serial No. 747,420

5 Claims. (Cl. 242—83)

This application is a continuation-in-part of my copending application Serial No. 509,209, filed May 18, 1955 and entitled "Apparatus for Distributing Filamentary Material into Coil Form."

The present invention relates generally to apparatus for collecting strands, and relates more particularly to improvements in the apparatus disclosed in my copending application, which improvements enable collection of a strand in a continuous succession of coils having varying radii.

An object of the invention is to provide new and improved apparatus for collecting strands.

A further object of the invention is to provide apparatus for collecting a strand in a continuous succession of coils having varying radii.

Yet another object of the invention is to provide, in combination with the strand-distributing apparatus disclosed in my copending application, apparatus for collecting the strand in a continuous succession of coils having alternately increasing and decreasing radii.

An apparatus for collecting a strand being distributed along a descending helical path into a container, illustrating certain features of the invention, may include means for rotating the container about the axis of the helix defined by the descending strand in one direction, and means for rotating the container about the same axis in the opposite direction, in order to collect the strand in a continuous succession of coils having varying radii. Means may be provided for rotating the container at uniformly increasing then uniformly decreasing speeds in one direction, means for rotating the container at uniformly increasing then uniformly decreasing speeds in the opposite direction, and means for operating the rotating means alternately, so that the coils have alternately increasing and decreasing radii.

Other objects and advantages of the invention will appear from the following detailed description of a specific embodiment thereof, when read in conjunction with the appended drawings, in which:

Fig. 1 is a front elevation, partially in section, of a strand-collection apparatus illustrating the invention, a portion of the figure corresponding generally to Fig. 3 of my copending application, illustrating one form of distributing apparatus as in my copending application;

Fig. 2 is a graph indicating the rotational speed of a container for the strand as a function of time according to a preferred cycle of operation, and

Fig. 3 is a schematic drawing of a control circuit for operating the apparatus of Fig. 1 in accordance with the principles of the invention so as to achieve the cycle illustrated in Fig. 2.

Referring now in detail to the drawings and in particular to Fig. 1, there is shown a strand-distributing apparatus generally in accordance with Fig. 3 of my copending application, in combination with a means for rotating the strand receiver in accordance with the principles of this invention. For convenience, the elements forming a part of my copending application have been

given the numerals used in my copending application and the elements forming a part of this application only have been given numerals starting with the numeral 200.

As disclosed in my copending application as illustrated in Fig. 1, the distributing apparatus includes a supporting ring 101, having a sprocket 102 formed around the outer periphery thereof and rotatable in a central bearing 105. The ring 101 is designed to support a horizontal, annular disc 106, which is rotatable with the ring 101 about a central bearing 107. The foregoing elements will be described in more detail hereinafter.

The strand-distributing apparatus illustrated in Fig. 1 is designed to coil filamentary material such as a strand 111, which may be, for example, a bare wire or an insulated conductor, into a container such as a barrel 110 of fibrous material. The barrel 110 is preferably provided with a cylindrical core 112 at the center thereof for constraining the strand 111 being coiled to lie in an annular area defined between the outer surface of the core 112 and the inner surface of the barrel 110.

As described in my copending application, the strand 111 passes first between a pair of metering rollers 128—128 forming a part of a conventional counter unit, designated generally by the numeral 129; thence downward through a fixed, hollow shaft 117; thence around each of three guide pulleys 130, 131 and 132; and thence to a grooved, positively-driven capstan 119, which serves to advance the strand 111 and distribute the same in a descending helical path into the barrel 110 in the form of a continuous succession of coils.

An endless belt 127 passes about a portion of the periphery of the capstan 119 and also about portions of the periphery of three idler sheaves 120, 122 and 123, which are spaced about the capstan 119 and function to tension the belt 127 and determine the angle of contact (preferably about 180°) between the belt 127 and the capstan 119, thus to regulate the angle at which the strand 111 is advanced by the capstan 119.

The capstan 119 and the sheaves 120, 122 and 123 are all mounted for rotation about their own axes to a mounting plate 125, which in turn is revolvable about the fixed shaft 117, the axis of the shaft 117 being made coincident with the center line of the barrel 110 and thus with the axis of the coils to be formed. For this purpose, the mounting plate 125 is secured near the outer surface of the horizontal, annular disc 106, which is mounted in the bearing 107 for rotation about the fixed shaft 117.

The rotatable disc 106 is connected by a plurality of adjustable rods 109—109 to the supporting ring 101, which is formed with the sprocket 102 permitting rotation thereof by a motor 121 through a chain 124, the ring 101 also being supported for rotation about the fixed shaft 117 by the bearing 105. The first two guide pulleys 130 and 131 are mounted to the disc 106 and the third guide pulley 132 is mounted to one of the rods 109—109, so that all of these pulleys revolve with the capstan 119 so as to maintain a fixed feeding position relative thereto. The shaft 117, the motor 121 and the counter 129 are all mounted to a fixed platform 115 near the top of the apparatus.

A fixed, beveled sun gear 113 is secured about the fixed shaft 117 and meshes with a bevel gear 118, which in turn is connected by a shaft 114 to the capstan 119 to cause rotation thereof for advancing the strand 111. The shaft 114 is journaled in a bearing 116, which is secured to the plate 125. In order to distribute the strand 111 into the barrel 110, the motor 121 is energized to rotate the supporting ring 101 and the disc 106 connected thereto by the rods 109—109 to revolve the mounting plate 125 and the capstan 119 connected thereto about the fixed shaft 117.

Assuming that the ring 101 is rotated by the motor

121 in a clockwise direction, as viewed from the top of Fig. 1 and indicated by an arrow, then the capstan 119 will also revolve in a clockwise direction about the fixed shaft 117 as a center, which as previously mentioned is made coincident with the center line of the barrel 110. As the capstan revolves in a clockwise direction about the shaft 117, the bevel gear 118 carried thereby will travel about the fixed sun gear 113 and thereby induce rotation of the gear 118 about its own axis. As the gear 118 rotates, the capstan 119 will also rotate on the shaft 114 in a counterclockwise direction as viewed in Fig. 1 and indicated by an arrow.

The strand 111 will thus be advanced by the rotation of the capstan 119, but the point where the strand leaves the capstan (that is, the portion of the capstan 119 which is last to contact the strand 111) is caused to revolve about the axis of the coil to be formed at substantially the same speed as the speed of the strand leaving the capstan 119, but in the opposite direction thereto. With this arrangement, the strand 111 advanced by the capstan 119 is continuously distributed in a descending helical path into the barrel 110 forming a coil therein.

The equalization of these speeds is merely a matter of design and is accomplished by selecting the proper relative sizes for the sun gear 113, the bevel gear 118, and the capstan 119. The distance between the axis of the sleeve 117 and the point near the surface of the sheave 123 where the strand 111 leaves the capstan 119 (the radius of revolution of the point where the strand leaves the capstan) is preferably fixed at substantially the mean radius between the inner radius of the barrel 110 and the outer radius of the cylindrical core 112.

A cylindrical, shell-like deflecting member 171 (shown with the front portion broken away) is mounted above the barrel 110 and serves to constrain the advancing strand 111 to fall in the desired descending helical path. A plurality of curved rods 175-175 are pivotably secured to the deflecting member 171 and are normally maintained in a retracted position, as illustrated in Fig. 1. When a predetermined length of the strand 111 has passed between the rollers 128-128 of the counter 129, a number of solenoids 181-181 are energized to pivot the rods 175-175 toward the shaft 117 to positions below and in the path of the descending strand coils in order to accumulate the following strand 111, while the then-full barrel 110 is removed from the apparatus and an empty barrel is substituted therefor.

The counter 129 may also energize an automatic cutting means (not shown herein, but described in detail in my copending application) in order to sever the strand 111 extending between the then-full barrel 110 and the accumulator rods 175-175 so as to facilitate the removal of the full barrel and the substitution therefor of an empty barrel without discontinuing the operation.

Up to this point, the apparatus illustrated is substantially the same as that shown and described in the second embodiment of my copending application, it being understood that the apparatus illustrated in the first embodiment of my copending application would function equally well and further that any other apparatus could be employed which would function to accomplish the desired step of distributing the strand in a descending helical path into the container.

In combination with the strand-distributing apparatus just described, it is now proposed to add means for rotating the container about the axis of the helix defined by the descending strand (which is coincident with the center line of the coils being collected in the container and preferably with the central axis of the barrel 110, as illustrated in Fig. 1) alternately in opposite directions in order to collect the strand in a continuous succession of coils having varying radii. Preferably, the container is rotated according to a repeating, four-part cycle: (1) uniformly increasing speed in one direction, (2) uniformly decreasing speed in the same direction, (3) uni-

formly increasing speed in the opposite direction, and then (4) uniformly decreasing speed in the opposite direction. Also, preferably, the duration of each quarter of the cycle is made equal and the maximum speed in both directions is made equal.

Utilizing the distributing apparatus illustrated in Fig. 1, the strand 111 is discharged by the capstan 119 in a descending helix, which is directed toward the mean radius between the inside of the container 110 and the outside of the core 112 and, when the barrel 110 is stationary, the strand coils will tend to assume the mean radius. When the barrel 110 is rotated at increasing speeds in the same direction that the strand is being fed thereto (a clockwise direction as viewed from the top of Fig. 1 and hereinafter termed the forward direction), the strand coils will assume successively larger radii until the barrel 110 reaches its maximum speed in the forward direction, at which time the strand coils will attain their maximum radius.

The maximum speed of rotation of the barrel 110 is so regulated that the radius of the strand coils collected at that time is substantially equal to, or slightly less than, the radius of the barrel 110, so that the strand coils will lie adjacent to the inner wall of the barrel 110 at that time.

The barrel 110 is then rotated at decreasing speeds in the forward direction so that the radii of the coils will be successively decreased until the strand again falls along the mean radius when the container 110 is stationary.

The barrel 110 is next rotated at gradually increasing speeds against the direction of distribution of the strand thereto (counterclockwise as viewed from the top of Fig. 1 and hereinafter termed the reverse direction), whereby the strand is distributed in coils having successively smaller radii until the minimum radius is reached when the barrel 110 attains its maximum speed in the reverse direction. The maximum speed in the reverse direction is so regulated that the coils then have a radius equal to, or slightly greater than, the radius of the core 112 so that strand coils will be adjacent to the outer wall of the core 112. The rotational speed in the reverse direction is then decreased so that the strand 111 will be distributed in coils of increasing radii until the barrel 110 is again stationary, at which time the coils will again be formed with the mean radius.

Fig. 2 is a graph illustrating the preferred relationship between time and the speed and direction of rotation of the barrel 110 over one complete cycle of operation. At a starting time t_0 , the barrel 110 will be assumed to be stationary, so that the strand 111 is distributed in a coil having the mean radius. During a predetermined time interval between t_0 and t_1 , the barrel 110 is rotated at uniformly increasing speed in the forward direction (clockwise as viewed from the top of Fig. 1) until a maximum speed is reached at the time t_1 , at which time the strand will be distributed in a coil having the maximum radius. Between the times t_1 and t_2 , the barrel 110 is rotated at a uniformly decreasing speed in the forward direction until at the time t_2 the barrel is stationary and the strand 111 is again distributed in a coil having the mean radius.

The barrel 110 is then rotated at a uniformly increasing speed in the reverse direction (counterclockwise as viewed from the top of Fig. 1) between the times t_2 and t_3 . At the time t_3 , the maximum speed in the reverse direction is reached and the strand 111 is distributed in a coil having a minimum radius. The barrel 110 is then rotated at uniformly decreasing speeds in the reverse direction until the time t_4 is reached, at which time the barrel 110 is again stationary so that the strand 111 is distributed in a coil having the mean radius. At this time, one complete cycle of operation has been completed and the barrel 110 is then rotated again at increasing speeds in the forward direction.

It is preferred that the time intervals between t_0 , t_1 , t_2 ,

t_3 and t_4 should all be equal to one quarter of the total cycle and, further, that the maximum speeds in both directions of rotation should be equal to each other. With this arrangement, the container-speed vs. time chart will appear substantially as illustrated in Fig. 2.

As an illustrative example, a strand 111 such as an insulated wire may be advanced by the capstan 119 at a speed of approximately 2000 feet per minute and distributed according to the principles of the invention into a barrel 110 having an inside radius of 21 inches using a core 112 having a radius of 15 inches. With this arrangement, the strand 111 is distributed in coil form into an annular area having a width of 6 inches and a mean radius of 18 inches, which is the radius which the strand coils tend to assume when the barrel 110 is stationary.

Under these conditions, the barrel 110 is rotated at a uniformly increasing speed in the forward direction up to a maximum speed of about 37 r.p.m. at time t_1 , the strand 111 being distributed in coils of uniformly increasing radius between the mean radius of 18 inches and the radius of the barrel 110, 21 inches. After attainment of the maximum speed of 37 r.p.m. in the forward direction, the rotational speed is then reduced at a uniform rate back to zero at time t_2 , at which time the strand coils again have the mean radius of 18 inches.

The barrel is next rotated in the reverse direction at a uniformly increasing speed up to a maximum speed of about 37 r.p.m. at time t_3 , at which time the strand coils have the minimum radius of 15 inches, the radius of the core 112. The barrel 110 is finally rotated at uniformly decreasing speeds in the reverse direction reaching zero at time t_4 , at which time the coils again have the mean radius of 18 inches and one full cycle has been completed.

A preferred apparatus for rotating the barrel 110 alternately in both directions and at the controlled variable speeds just described is illustrated at the bottom of Fig. 1. The barrel 110 is mounted on a turntable 200 for rotation therewith. The turntable 200 is rotated through a pair of bevel gears 201-201 by a reversible, variable speed A.C. motor 202, which is suitably mounted within a recess in the factory floor. A relatively long portion 203 of the output shaft 204 of the motor 202 is threaded and a block 206 having an internally threaded aperture therethrough is received about the threaded portion 203 for reciprocating, longitudinal movement therewith when the shaft 204 is rotated by the motor 202 alternately in opposite directions.

An electrical tap 207 depends from the block 206 and is designed to ride along the periphery of a potentiometer, designated generally by the numeral 208 and designed to control the speed of rotation of the motor 202. A pair of limit switches 209 and 210 are mounted at opposite ends of the potentiometer 208 and are designed to be closed alternately and momentarily by the reciprocating block 206 when the block reaches the extreme left and right positions, respectively, as viewed in Fig. 1. Momentary closure of the limit switches 209 and 210 is designed to initiate, alternately and respectively, rotation of the barrel 110 in the forward and reverse directions.

Referring now to the control circuit illustrated in Fig. 3, the block 206, the tap 207, the potentiometer 208, and the limit switches 209 and 210 are all illustrated schematically at the top of the figure, with the balance of the control circuit shown below. The potentiometer 208 includes two separate coils 211 and 212 of resistance wire, along which the tap 207 moves. The central ends of the coils 211 and 212 are wound very close together but are not electrically connected, the tap 207 being made sufficiently wide to bridge the ends of the two coils 211 and 212 when in the central position thereof.

In order to provide for the desired plan of operation described earlier and illustrated in Fig. 2, four cam-operated switches 213, 214, 215 and 216 are provided,

which are actuated respectively by four timing cams 218, 219, 220 and 221. The cams are rotated at a predetermined constant speed in a counterclockwise direction, as viewed in Fig. 3, by a control motor 222, which drives a common cam shaft 223 through a pair of speed-reducing, control gears 224-224.

The gears 224-224 are selected so as to provide a desired synchronism between the speed of rotation of the cams and the travel of the block 206, the cams being rotated at such speed that they will complete exactly one full revolution for each full cycle of operation (t_0-t_4). For convenience in understanding the operation of the control circuit, the position of the reciprocating tap 207 at each of the times (t_0-t_4) depicted in Fig. 3 is indicated at the top of Fig. 3, with arrows showing the direction of travel of the block 206 at each time. Also, the corresponding state of operation (open-or-closed) of the cam-operated switches 213-216 is indicated at the bottom of Fig. 3.

The motor 202 is illustrated schematically in Fig. 3 as a reversible, variable-speed, A.C. motor having three conductors 226, 227 and 228 connected to the field thereof, the conductor 227 being a common connection at all times. When a potential is applied across the conductors 226 and 227, the motor 202 rotates the turntable 200 and thus the container 110 in the forward direction. Conversely, when a potential is applied across the conductors 227 and 228, the barrel 110 is rotated in the reverse direction. The motor 202 may be energized from a suitable A.C. source 230 through the primary 231 and a secondary 232 of a transformer designated generally by the numeral 233. The transformer 233 is also provided with secondaries 234 and 235, which may be connected to supply current to energize a pair of control relays 236 and 237, respectively.

The relay 236 is energized whenever the limit switch 209 is closed momentarily (at the times t_0 and t_4) by the block 206, which is the operating state at the time t_0 depicted in Fig. 3. When the relay 236 is so energized, a latching contact 238 thereof is closed to maintain the energization circuit therefor (assuming that the cam-operated switch 213 is closed), and an operating contact 239 is closed to permit power to be supplied from the secondary 232 to the motor 202 through the lines 226 and 227 in order to rotate the barrel 110 in a forward direction.

The relay 237 operates in a similar manner to direct rotation of the barrel 110 in the reverse direction, the relay 237 being energizable from the secondary 235 when the limit switch 210 is closed (at the time t_2). The relay 237 is also provided with a latching contact 241 to maintain the energization thereof (assuming that the cam-operated contact 216 is closed) and an operating contact 242, which operates to energize the motor 202 from the secondary 232 across the alternate lines 227 and 228.

The cam 218 is designed so that the switch 213 is closed for one-half of the cycle between the times t_0 and t_2 , the latching circuit for the relay 236 including the switch 213 as well as the relay contact 238 so that, once energized at the time t_0 , the relay 236 will remain energized to direct forward rotation until the switch 213 is opened by the cam 218 when the first half of the cycle is completed at the time t_2 .

When the relay 236 is energized, the motor 202 is operated to rotate the barrel 110 in the forward direction since the motor circuit is then completed between the conductor 226, the operating contact 239, the secondary 232, the tap 207, the full length of the resistance coil 211, the cam-operated switch 215 (which is maintained closed during the time interval t_0-t_1 by the shape of the cam 220, as illustrated in Fig. 3), and the common conductor 227.

Since the full length of the resistance coil 211 is now

in the motor circuit, the motor will start to rotate the barrel 110 at a slow speed in the forward direction in order to collect the strand 110 in coils having a radius slightly larger than the mean radius. As the motor rotates in the forward direction, the block 206 will travel along the threaded portion 203 of the motor shaft 204, from left to right as illustrated in Figs. 1 and 3, which will cause the tap 207 to move to the right and thus tap less resistance from the resistance coil 211. As less resistance is tapped, the motor 202 increases uniformly in speed to distribute the strand 111 in coils of successively larger radii until the maximum speed is reached at the time t_1 , when none of the resistance 211 is in the motor circuit and the strand coils have a radius substantially equal to that of the barrel 110.

At the time t_1 , the switch 215 is opened by the cam 220 and the switch 214 is closed by the cam 219, due to the opposing configurations of these cams, illustrated in Fig. 3, the cam-operated switches 213 and 216 not being affected at this time. When the switch 214 closes, the motor 202 will continue rotating at its maximum speed since the tap 207 bridges the resistance coils 211 and 212; however, the motor circuit is now closed through the tap 207, an end portion of the resistance 212, and the switch 214 (rather than through the tap 207, a portion of the resistance 211, and the switch 215 as was the case during the interval between the times t_0 and t_1).

The block 206 and the tap 207 continues to move to the right so that an increasing amount of the resistance coil 212 is placed in the motor circuit and the radius of the coils decreases until the time t_2 is reached, at which time the full length of the resistance 212 is in circuit, the speed of the motor is almost zero, and the coil radius is again the mean radius.

At the time t_2 , the oppositely acting cams 218 and 221 operate to open the switch 213 and close the switch 216, respectively. The opening of the switch 213 operates to break the latching circuit for the relay 236 so as to open the operating contact 239 and disconnect the motor 202 from energization across the lines 226 and 227. At the time t_2 , the limit switch 210 is momentarily closed by the block 206 at the end of its travel from left to right, which energizes the control relay 237 from the secondary 235. When the relay 237 is energized, its latching contact 241 is closed and the relay 237 is maintained energized, even though the limit switch 210 opens, through the latching contact 241 and the now-closed switch 216. This circuit is maintained between the times t_2 and t_4 due to the design of the operating cam 221.

When the relay 237 is energized, the operating contact 242 is closed, which causes energization of the motor 202 through the conductor 228, the contact 242, the secondary 232, the tap 207, the entire portion of the resistance coil 212, the still-closed switch 214, and the common conductor 227. At this time, the motor 202 begins rotating at a slow speed in the reverse direction so as to distribute the strand 111 in coils of decreasing radii below the mean radius.

The block 206 will now travel from right to left, as viewed in Figs. 1 and 3, placing successively smaller portions of the resistance 212 in circuit with the motor 202 so as to increase the motor speed until the maximum speed in the reverse direction is reached at the time t_3 . At the time t_3 , the switch 214 is opened by the operating cam 219 and the switch 215 is closed by the operating cam 220, so that the motor 202 is now energized through a small portion of the resistance 211 and the switch 215, rather than through a portion of the resistance 212 and the switch 214 as was the case between the times t_2 and t_3 .

The motor 202 now rotates at a decreasing speed between the times t_3 and t_4 , the tap 207 travelling from right to left along the resistance 211 so as to increase the

10

amount of resistance in series with the motor 202 and thus to slow the motor down to a minimum speed near zero at the time t_4 , when the full length of the resistance 211 is in series with the motor 202. The time t_4 corresponds to the time t_0 , the coils again having the mean radius but the apparatus having completed one full cycle of operation. At the time t_4 , the limit switch 209 is again closed momentarily to energize the relay 236 and start the motor 202 running once more in the forward direction. The cam-operated switch 213 is also reclosed at the time t_4 to maintain the energization of relays 236, the relay 237 being de-energized by the reopening of the cam-operated switch 216.

It will be manifest that this invention is not limited to the specific details described in connection with the above embodiment of the invention, but that various modifications may be made without departing from the spirit and scope thereof.

What is claimed is:

20 1. In combination with apparatus for coiling a strand, including a container in which the strand is to be coiled, a capstan mounted above the container for continuously advancing a length of the strand, and means for causing those portions of the capstan which are last to contact the strand to revolve about the axis of the coil to be formed at substantially the same speed as the speed of the strand leaving the capstan but in the opposite direction thereto, whereby the strand advanced by the capstan is continuously distributed in a descending helical path into the container; the improvement which comprises means for rotating the container about the axis of the coil to be formed alternately with and against the direction of distribution of the strand thereto in order to collect the strand in a continuous succession of coils 30 having varying radii.

35 2. In combination with apparatus for coiling a strand, including a container in which the strand is to be coiled, a capstan mounted above the container for continuously advancing a length of the strand, and means for causing those portions of the capstan which are last to contact the strand to revolve about the axis of the coil to be formed at substantially the same speed as the speed of the strand leaving the capstan, but in the opposite direction thereto, the central axis of the container being coincident with the axis of the coil to be formed, whereby the strand advanced by the capstan is continuously distributed in a descending helical path into the container; the improvement which comprises: reversible, variable-speed means for rotating the container about its central axis; first means for controlling the operation of said rotating means so that the container is rotated at uniformly increasing speeds in the direction of distribution of the strand thereto for a first predetermined time interval, during which first time interval the strand is collected in coils of increasing radii above a normal radius which exists when the container is stationary; second means operable after the first time interval for controlling the operation of said rotating means so that the container is rotated at uniformly decreasing speeds in the same direction for a second predetermined time interval, during which second time interval the strand is collected in coils of decreasing radii approaching the normal radius; third means operable after the second time interval for controlling the operation of said rotating means so that the container is rotated at uniformly increasing speeds in the reverse direction for a third predetermined time interval, during which third time interval the strand is collected in coils of decreasing radii below the normal radius; and fourth means operable after the third time interval for controlling the operation of said rotating means so that the container is rotated at uniformly decreasing speeds in the reverse direction for a fourth predetermined time interval, during which fourth time interval the strand is collected in coils of increasing radii approaching the normal radius; said first controlling means being again

operable after the fourth time interval to provide a continuous cycle of operation.

3. In combination with apparatus for coiling a strand, including a collecting barrel having a central core defining an annular area between the barrel and the core within which the strand is to be coiled, a capstan mounted above the barrel for continuously advancing a length of the strand, and means for causing those portions of the capstan which are last to contact the strand to revolve about the axis of the coil to be formed at substantially the same speed as the speed of the strand leaving the capstan, but in the opposite direction thereto, the central axis of the barrel being coincident with the axis of the coil to be formed, the capstan being so arranged that the strand advanced thereby is continuously distributed in a descending helical path into the barrel forming a coil therein which normally tends to assume the mean radius between the barrel and the core; the improvement which comprises: reversible, variable-speed means for rotating the barrel about its central axis; first means for controlling the operation of said rotating means so that the barrel is rotated at uniformly increasing speeds in a forward direction, the direction of distribution of the strand thereto, reaching a maximum speed at the end of a first predetermined time interval, during which first time interval the strand is collected in coils of increasing radii between the mean radius and the radius of the barrel; second means operable after the first time interval for controlling the operation of said rotating means so that the barrel is rotated at uniformly decreasing speeds in the forward direction, approaching zero at the end of a second predetermined time interval equal to the first such interval, during which second time interval the strand is collected in coils of decreasing radii approaching the mean radius; third means operable after the second time interval for controlling the operation of said rotating means so that the barrel is rotated at uniformly increasing speeds in the reverse direction, reaching a maximum speed in the reverse direction equal to the maximum speed in the forward direction at the end of a third predetermined time interval equal to each of the first and second such intervals, during which third time interval the strand is collected in coils of decreasing radii between the mean radius and the radius of the core; and fourth means operable after the third time interval for controlling the operation of said rotating means so that the barrel is rotated at uniformly decreasing speeds in the reverse direction, approaching zero at the end of a fourth predetermined time interval equal to each of the other such intervals, during which fourth time interval the strand is collected in coils of increasing radii approaching the mean radius; said first controlling means being again operable after the fourth time interval to provide a continuous cycle of operation.

4. In combination with apparatus for coiling a strand, including a container in which the strand is to be coiled, a capstan mounted above the container for continuously advancing a length of the strand, and means for causing those portions of the capstan which are last to contact the strand to revolve about the axis of the coil to be formed at substantially the same speed as the speed of the strand leaving the capstan, but in the opposite direction thereto, whereby the strand advanced by the capstan is continuously distributed in a descending helical path into the container; the improvement which comprises: a reversible, variable-speed motor for rotating the container about the axis of the coil to be formed, and means for controlling the operation of said motor so that the container is rotated first at increasing speeds in the direction of distribution of the strand thereto, second at decreasing speeds in the same direction, third at increasing speeds

in the reverse direction, and finally at decreasing speeds in the reverse direction, whereby the strand is distributed in a continuous succession of coils having increasing and then decreasing radii.

5. In combination with apparatus for coiling a strand, including a collecting barrel having a central core defining an annular area between the barrel and the core within which the strand is to be coiled, a capstan mounted above the barrel for continuously advancing a length of the strand, and means for causing those portions of the capstan which are last to contact the strand to revolve about the axis of the coil to be formed at substantially the same speed as the speed of the strand leaving the capstan but in the opposite direction thereto, the central axis of the barrel being coincident with the axis of the coil to be formed, the capstan being so arranged that the strand advanced thereby is continuously distributed in a descending helical path into the barrel forming a coil therein which normally tends to assume the mean radius between the barrel and the core; the improvement which comprises: a reversible, variable-speed motor for rotating the barrel about its central axis; timing means; first switching means operated by said timing means for controlling the operation of said motor so that the barrel is rotated at uniformly increasing speeds in a forward direction, the direction of distribution of the strand thereto, said motor reaching a maximum speed at the end of a first predetermined time interval controlled by said timing means, during which time interval the strand is collected in coils of increasing radii between the mean radius and the radius of the barrel; second switching means operated by said timing means at the end of the first time interval for controlling the operation of said motor so that the barrel is rotated at uniformly decreasing speeds in the forward direction, the speed of said motor approaching zero at the end of a second predetermined time interval controlled by said timing means and equal to the first such interval, during which second time interval the strand is collected in coils of decreasing radii approaching the mean radius; third switching means operated by said timing means at the end of the second time interval for controlling the operation of said motor so that the barrel is rotated at uniformly increasing speeds in the reverse direction, said motor reaching a maximum speed in the reverse direction equal to the maximum speed in the forward direction at the end of a third predetermined time interval controlled by said timing means and equal to each of the first and second such intervals, during which third time interval the strand is collected in coils of decreasing radii between the mean radius and the radius of the core; and fourth switching means operated by said timing means at the end of the third time interval for controlling the operation of said motor so that the barrel is rotated at uniformly decreasing speeds in the reverse direction, the speed of said motor approaching zero at the end of a fourth predetermined time interval controlled by said timing means and equal to each of the other such intervals, during which fourth time interval the strand is collected in coils of increasing radii approaching the mean radius; said first controlling means being again operated by said timing means at the end of the fourth time interval to provide a continuous cycle of operation.
